UNITED STATES PATENT OFFICE.

WALLACE M. JAMES, OF EYOTA, MINNESOTA.

DRAFT-EQUALIZER.

SPECIFICATION forming part of Letters Patent No. 727,956, dated May 12, 1903.

Application filed May 3, 1902. Serial No. 105,867. (No model.)

To all whom it may concern:

Be it known that I, WALLACE M. JAMES, a citizen of the United States, residing at Eyota, in the county of Olmsted and State of Minnesota, have invented a Compound Five or Six Horse Evener, of which the following is a specification.

This invention relates to new and useful improvements in draft-equalizers; and the essential purpose of the same is to provide a device involving a minimum number of parts and which may be adjusted for use with either five or six horses. The equalizer is especially adapted for attachment to gang-plows and harvester-machines, and the draft attachments are disposed so as to distribute the positions of the animals.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a top plan view showing the parts arranged for use as a five-horse evener. Fig. 2 is a longitudinal sectional view of the device, whiffletrees not shown.

Corresponding and like parts are referred to in the following description and indicated in all the views of the drawings by the same reference characters:

The evener comprises, essentially, a draft-lever 1, which is connected to the implement to which the device is applied by any suitable connection, such as a link or clevis 2, and an equalizing-lever 3 is fulcrumed intermediate the ends of the draft-lever, and said equalizing-lever comprises spaced bars 3^a and 3^b, these bars being brought together at their outer ends, a fastening connecting said bars at this point. A clevis 4 or like connection is disposed at the end of the draft-lever opposite that upon which the equalizing-lever is disposed, and this clevis is adapted to connect a doubletree to the draft-lever. The equalizing-lever is fulcrumed intermediate its ends, and a singletree 5 is adapted for con-

nection with the outer end of the equalizing-lever. A draft-bar 6, comprising a single bar bent upon itself to form spaced ends, is connected to the inner end of the equalizing-lever. The said spaced ends 7 are secured to the respective members 3^a and 3^b of the equalizing-lever 3 by any suitable fastening means. It is purposed to attach a doubletree to the draft-bar 6 when the equalizer is used as a five-horse evener. Openings 8 upon the draft-lever 1 are adapted to afford adjustment for the fastening by which the equalizing-lever is fulcrumed to the said draft-lever. A series of openings 9 are also provided upon the draft-lever, by which the point of fulcrum for the said draft-lever in its connection with the harvesting-machine or plow or other implement may also be adjusted.

When the equalizer is used for a six-horse evener, the fastening by which the equalizing-lever 3 is pivoted to the draft-lever is adjusted so as to pass through the openings in the spaced members 3^a and 3^b of the said equalizing-lever nearest the inner ends thereof. Also the fastening by which the clevis 2 is secured to the draft-lever 1 is adjusted so as to pivot the lever through the opening nearer the end of the draft-lever upon which the equalizing-lever is disposed. The points of fulcrum being arranged as above explained, any ordinary means for adapting three horses to the draft-bar 6 may be utilized, and the equalizer may be thus adapted for use as a six-horse evener. The spaced bars of the equalizing-lever are disposed upon opposite sides of the draft-lever, bringing the several parts of the device in approximately the same plane, this being of importance in this class of devices.

The arrangement of the several parts is such that the animals are disposed with relation to the equalizer in positions in which they cannot in any way be impeded in their movement by each other, which is deemed an essential advantage for the special disposal of the said parts.

Having thus described the invention, what is claimed as new is—

In a draft-equalizer, and in combination with a draft-lever adjustably fulcrumed intermediate its ends, a doubletree secured to one end of the draft-lever, an equalizing-le-

ver adjustably pivoted intermediate its ends to the opposite end portion of the draft-lever and comprising spaced bars disposed upon opposite sides of the draft-lever, said bars 5 having their outer ends brought together, a singletree secured to the outer end of the equalizing-lever, and a draft-bar comprising a single bar bent to form spaced end portions, the spaced end portions of the draft-bar be-

ing respectively secured to the inner ends of the spaced bars of the equalizing-lever, and a doubletree adapted to be secured to the aforesaid draft-bar, substantially as described.

WALLACE M. JAMES.
